[57] CLAIM

The ornamental design for a motor home front panel unit exterior surface, as shown and described.

DESCRIPTION

FIG. 1 is a front perspective view of the motor home front panel unit exterior surface showing the new design;

FIG. 2 is a front elevational view thereof;

FIG. 3 is a left side elevational view thereof;

FIG. 4 is a right side elevational view thereof; and,

FIG. 5 is a top plan view thereof.

The broken line showing of a motor home body in FIG. 1 of the drawing is for illustrative purposes only and forms no part of the claimed design.

FIG. 1

FIG. 3

FIG. 2

FIG. 4

FIG. 5
